UNITED STATES PATENT OFFICE.

FORREST G. THACKABERRY, OF TAMPICO, ILLINOIS.

INDUCTANCE-COIL.

1,080,605.

Specification of Letters Patent.

Patented Dec. 9, 1913.

Application filed August 7, 1912. Serial No. 713,887.

To all whom it may concern:

Be it known that I, FORREST G. THACKABERRY, a citizen of the United States, residing at Tampico, in the county of Whiteside, 5 State of Illinois, have invented certain new and useful Improvements in Inductance-Coils; and I do hereby declare the following to be a full, clear, and exact description of the invention, such as will enable others 10 skilled in the art to which it appertains to make and use the same.

This invention relates to inductance coils.

The object of the invention resides in the provision of a resistance coil which includes 15 an improved construction whereby the resistance offered by the coil to the circuit in which it is included may be increased and diminished as circumstances may require, the coil being particularly useful in effecting 20 the "tuning" of wireless apparatus.

With the above and other objects in view the invention consists in the details of construction and in the arrangement and combination of parts to be hereinafter more 25 fully described and particularly pointed out in the appended claim.

In describing the invention in detail reference will be had to the accompanying drawings wherein like characters of reference denote corresponding parts in the 30 several views, and in which—

Figure 1 is a plan view of the invention. Fig. 2 a side view of same. Fig. 3 a section on the line 3—3 of Fig. 2, and Fig. 4 a partial section on the line 4—4 of Fig. 1.

Referring to the drawings, the device is shown as comprising a frame A which includes a pair of spaced end members 10 and 11 and core members 12 and 13 connecting 40 the end members 10 and 11, said core members being disposed in a common horizontal plane. It will of course be understood that the end members 10 and 11 and the core members 12 and 13 are constructed of suitable non-conducting material. Mounted in the end member 10 between the core members 12 and 13 is a binding post 14, while another binding post 15 is similarly mounted in the end member 11. Connecting the end 45 members 10 and 11 above the core member 12 is a metallic rod 16, while another metallic rod 17 connects the end members 10 and 11 and is disposed above the core member 13. The rod 16 is electrically connected with the 50 binding post 14 by means of a conductor element 18, while the rod 17 is electrically

connected to the binding post 15 by means of a conductor element 19. Having one end connected to the binding post 15 is a relatively fine insulated wire 20. This wire is 50 wound upon the core member 12 in the desired number of layers and then extended across to the core member 13 as at 21 and then wound upon said core member 13 in the desired number of layers and terminates at 55 22 in spaced relation to the end member 11. It will be noted that the point where the wire 20 is carried across from the core 12 to the core member 13 is disposed in spaced relation to the end member 10. Slidably mounted on the rod 16 is a metallic sleeve 23, while a corresponding metallic sleeve is 60 slidably mounted on the rod 17. The insulation of the wire 20 disposed upon the core 12 is scraped off at a point directly beneath the rod 16 so as to expose the outer side of the wire coils but not to disturb the insulation between the coils themselves. This exposed portion of the wire coil on the core member 12 is adapted to be engaged at different 65 points by a contact finger 25 carried by the sleeve 23 and adapted further to pass out of engagement with the coils when the sleeve is moved to its limit toward the end member 10. Likewise the insulation on the wire 70 coils carried by the core member 13 is scraped off directly beneath the rod 17 and this exposed portion of the coil is adapted to be engaged by a contact finger 26 carried by the sleeve 24. This contact finger is also 75 adapted to engage the coils on the core member 13 at different points as the sleeve 24 is 80 adjusted on the rod 17 and further adapted to pass entirely out of engagement with the coils on the core member 14 when the sleeve 85 24 has been moved to its limit on the rod 17 toward the end member 11.

In the operation of the device same is connected in a given circuit through the medium of the binding posts 14 and 15. If 100 it is desired to offer the full resistance of the coil to the current of the circuit the sleeve 23 is adjusted to its limit of movement on the rod 16 toward the end member 10, while the sleeve 24 is adjusted to bring the contact finger 26 in engagement with the wire coil nearest the end member 11 and disposed upon the core member 13. The current will then pass through all of the coils of wire on both the core members 12 and 13 105 and the maximum resistance will be offered by the device to the current. By adjusting 110

the sleeve 24 toward the end member 10 it will be apparent that the resistance offered to the device by the current may be constantly diminished. By adjusting the sleeve 5 24 to the limit of its movement toward the end member 11 and then adjusting the sleeve 23 so as to engage the coil on the core member 12 nearest the end member 10 it will be apparent that only the resistance of the coils 10 on the core member 12 will be offered to the current and this resistance can be constantly diminished by adjusting the sleeve 23 toward the end member 11.

The resistance of the device may be entirely cut out by adjusting the sleeve 23 to the limit of its movement toward the end member 10 and the sleeve 24 to the limit of its movement toward the end member 11. In this last named position of the 20 sleeves 23 and 24 the device will serve as an efficient lightning arrester and thereby protect the apparatus associated therewith.

What I claim is:—

In a device of the class described, a non- 25 conducting frame including end members and core members connecting said end members, binding posts carried by said end members respectively, metallic rods connecting

the end members and disposed above respective core members, an insulated wire 30 having one end connected to one of said binding posts and then coiled about said core members successively, the insulation of the coils disposed beneath respective rods being removed to expose the wire, sleeves 35 slidably mounted on each of said rods, contact fingers carried by the sleeves respectively, each of said fingers being U-shaped and having its outer arm extending substantially parallel to the adjacent coil and 40 engaging the exposed portion of the latter throughout the greater portion of the extent of said arm and having its side edges in engagement with the walls formed by the adjacent removed portion of the insulation whereby the finger is guided in its movements, and an electrical connection between each of said rods and the other binding post.

In testimony whereof, I affix my signature, in presence of two witnesses.

FORREST G. THACKABERRY.
